UNITED STATES PATENT OFFICE.

HENRY PAULSON, OF CHICAGO, ILLINOIS.

CROSS-REFERENCE CATALOGUE INDEX.

1,403,622.

Specification of Letters Patent. Patented Jan. 17, 1922.

Application filed December 27, 1920. Serial No. 433,330.

To all whom it may concern:

Be it known that I, HENRY PAULSON, a citizen of the United States, residing at the city of Chicago, county of Cook, State of Illinois, have invented a new and useful Cross-Reference Catalogue Index, of which the following is a specification.

My invention relates to improvements in a catalogue index to accomplish which, I, in addition to the usual index which either precedes or follows the contents of such a work, place in a prominent position on each and every page of my catalogue, on which illustrations and prices of merchandise are printed, a section of index, containing cross-references, particularly appropriate to the page in question.

The drawing attached to this specification illustrates a catalogue page illustrating and quoting the prices on pliers, pliers being listed under the letter "P." In the upper left-hand corner (the upper right-hand corner may be used equally well) of the page appears a piece of cross-reference index, containing items which might be popularly supposed to list under the letter "P," but which are correctly listed under other classifications and consequently on other pages. The sample index, illustrated in the drawing, lists just such items and offers the page number on which these items are advertised. For examples:

The advantage of this improved system of indexing lies in the fact that easy access may be had to catalogue illustrations and price quotations on items which are popularly known under several different names. For example, pendant set keys. This might be classified under P (pendant tools) or under K—(keys) but is correctly classified under S—being a form of screwdriver. By means of my system of indexing, one who examines a catalogue in an endeavor to locate a particular item of interest to him, turns to the classification under which he believes that the item he is seeking, is listed. On failing to find the item listed therein, he consults the cross-reference index and learns the page number on which the item he seeks, is listed.

I claim:

An advertising merchandise catalogue, consisting of illustrating prints and price quotations, having on one or more of its pages a marginal index, in which there are listed descriptive names of items which might in true alphabetical sequence be correctly illustrated and priced on that selected page, but which are actually illustrated and priced elsewhere under a different descriptive name, to which latter page reference is made on the marginal index of the page in question.

HENRY PAULSON.
